UNITED STATES PATENT OFFICE.

CLYDE E. MORGAN, OF HOLDENVILLE, OKLAHOMA

MINE-CAR BRAKE

1,154,041.

Specification of Letters Patent. Patented Sept. 21, 1915.

Application filed June 24, 1915. Serial No. 26,097.

To all whom it may concern:

Be it known that I, CLYDE E. MORGAN, a citizen of the United States, residing at Holdenville, in the county of Hughes and State of Oklahoma, have invented certain new and useful Improvements in Mine-Car Brakes, of which the following is a specification, reference being had to the accompanying drawings.

This invention relates to an improved mine car brake and has for its primary object to provide a simple and effective hand operated brake for stopping the car upon an inclined section of the track.

The invention has for a more particular object to provide a brake for mine cars which are pulled by cables, whereby, in the event that the cables should break when the car is being pulled up an incline, the brakes will be automatically applied to stop the descent of the car and thus obviate possibility of injury or damage, which would otherwise result from its release.

It is an additional object of the invention to provide a brake of the above type embodying ratchet disks secured upon the spaced car wheels and pivotally mounted brake dogs normally and yieldingly held in engagement therewith, and manually operable means for simultaneously throwing the dogs to an inoperative position.

With the above and other objects in view, my invention consists in the novel features of construction, combination, and arrangement of parts to be hereinafter more fully described, claimed, and illustrated in the accompanying drawing, in which,

Figure 1 is a side elevation of a mine car equipped with my improved brake; Fig. 2 is an enlarged elevation of one of the brake devices, the brake dog being shown in an elevated inoperative position in dotted lines; and Fig. 3 is a section taken on the line 3—3 of Fig. 2.

Referring in detail to the drawing, 5 designates the body of the car which is mounted at its opposite ends upon the usual trucks having axles 6, upon the ends of which the wheels 7 are revolvably mounted to travel upon the track, indicated at 8. Upon the inner face of each of the wheels 7 on one side of the car, a ring or annulus 9 is securely riveted, bolted, or otherwise fixed in concentric relation to the wheel axle. This ring is provided upon its outer peripheral face with the ratchet teeth 10. To the side wall of the

car body 5, immediately above each wheel 7, a plate 11 is securely bolted, and this plate has a substantially semi-circular rib or projection 12 formed upon its face, the lower edge of which provides a horizontal shoulder 13. This curved shoulder extends in concentric relation to a stud 14, integrally formed upon the face plate in spaced relation to the said shoulder. The brake dog 15 tapers longitudinally from its larger end and is loosely engaged upon the stud 14. The free end of this dog has its end face properly beveled or inclined for contact with the end faces of the ratchet teeth 10 of the ring 9.

Upon the side wall of the car 5, above each of the plates 11, a bell crank lever 16 is fulcrumed. One arm of this lever extends horizontally and is connected by a rod 17 to a pin 18 which extends loosely through an opening provided in the dog 15 adjacent to its free end. A coil spring 19 is engaged upon said pin and bears at one of its ends against the dog 15. This spring is adapted to yieldingly hold the free end of the dog in contact with the ratchet teeth 10 on the ring 9. The other arms of the bell crank levers 16, which are vertically disposed, are connected by a rod 20, and to the said vertical arm of one bell crank lever, an operating bar 21 is also pivotally connected at one of its ends. This bar extends through a suitable guide loop 22 fixed upon the wall of the car, and with said loop a lug 23, formed upon the lower edge of the operating bar, is adapted to be engaged. To the wall of the car a pin 24 is fixed with which the laterally extending arm of the bell crank levers 16 is adapted to engage, whereby the downward movement of said arm is limited.

In the operation of the device, assuming that the brake dogs are in engagement with the ratchets 9, as shown in Fig. 2, when the car is being pulled by the cables up an incline, it will be seen that, if the cables should break and the car should start to descend the inclined track, the dogs 15, engaging the teeth of the respective ratchets, will effectively prevent rotation of the car wheels, thus stopping the descent of the car, so that no damage or injury will be done at the lower end of the inclined track. The spring 19 acting upon the brake dog will permit of the rotation of the car wheel in one direction so that the car may be readily pulled up the inclined track. When the car is traveling

upon a straight stretch of track and the
brake is not necessary, the dogs 15 may be
entirely disengaged from the ratchets by
the operator pulling upon the rod 21, and
5 engaging the lug 23 thereof with the keeper
member 22, as will be readily understood.

From the foregoing description, taken in
connection with the accompanying drawing,
the construction, manner of operation and
10 several advantages of the invention will be
clearly understood. It will be seen that I
have provided a simple and effective brake
which can be instantly applied when neces-
sary to check the speed of the car. The
15 brake device may, if desired, be provided
for each of the car wheels, and it will also
be apparent that the invention may be ap-
plied to vehicles other than mine cars, by
resorting to such necessary mechanical ex-
20 pedients as are requisite in the adaptation
of the device to a particular use. Owing to
the very few parts involved in the construc-
tion of the device, it will also be seen that
the same is very strong and durable in prac-
25 tical use and may be manufactured at small
cost.

While I have shown and described the
preferred construction and arrangement of
the several parts employed, it is manifest
30 that the invention is susceptible of consider-
able modification therein, and I, therefore,
reserve the privilege of resorting to all such
legitimate changes as may be fairly em-
bodied within the spirit and scope of the
35 invention as claimed.

Having thus fully described my invention,
what I desire to claim and secure by
Letters Patent is:—

1. The combination with a vehicle wheel,
40 of a brake ring fixed thereto, a brake dog
pivotally mounted at one end, a pin loosely
engaged in the free end of said dog, operat-
ing means connected to said pin to raise or
lower the free end of the dog with respect

to the brake ring, and a spring arranged 45
upon said pin bearing upon the dog to
yieldingly hold the same in braking engage-
ment with the ring.

2. The combination with a vehicle wheel,
of a brake ring fixed upon one face thereof 50
provided with ratchet teeth, a brake dog
pivotally mounted at one of its ends, a bell
crank lever, an operating rod connected to
one arm of said lever, a pin loosely engaged
in the free end of the dog, a connecting rod 55
between said pin and the other arm of the
bell crank lever to raise or lower the free
end of the dog with respect to the brake
ring, and a coil spring arranged upon said
pin and bearing upon the dog to yieldingly 60
hold the free end thereof in braking engage-
ment with the ratchet teeth on said ring.

3. The combination with the spaced ve-
hicle wheels, of a brake ring fixed to the
outer face of each wheel, brake dogs pivot-
ally mounted at one of their ends, and
means for raising and lowering the dogs
including bell crank levers, a pin loosely 65
mounted in the free end of each dog, con-
necting rods between the pins and one arm
of the respective levers, a rod connecting the
other arms of said levers, springs on said
pins to yieldingly hold the free ends of the
dogs in engagement with the brake rings,
an operating bar connected to the latter arm 70
of one bell crank lever adapted to actuate
said levers to simultaneously raise or lower
the free ends of the brake dogs, and means
for retaining the operating bar in one posi-
tion to hold the dogs out of engagement with 75
the brake rings.

In testimony whereof I hereunto affix my
signature in the presence of two witnesses.

CLYDE E. MORGAN.
